US00D963680S

(12) **United States Design Patent** (10) **Patent No.:** **US D963,680 S**
Clymer et al. (45) **Date of Patent:** **** Sep. 13, 2022**

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Erica L. Clymer**, Northampton, PA (US); **Benjamin F. Bard**, Zionsville, PA (US); **Jennifer Wong**, Breinigsville, PA (US); **Joel Hnatow**, Allentown, PA (US)

(73) Assignee: **Lutron Technology Company LLC**, Coopersburg, PA (US)

(**) Term: **15 Years**

(21) Appl. No.: **29/809,276**

(22) Filed: **Sep. 27, 2021**

Related U.S. Application Data

(63) Continuation of application No. 29/760,226, filed on Nov. 30, 2020, now Pat. No. Des. 934,282, which is a continuation of application No. 29/689,872, filed on May 2, 2019, now Pat. No. Des. 915,438, which is a continuation of application No. 29/601,123, filed on Apr. 19, 2017, now Pat. No. Des. 849,050, which is a continuation of application No. 29/531,293, filed on Jun. 24, 2015, now Pat. No. Des. 791,827.

CLAIM

The ornamental design for a display screen or portion thereof with graphical user interface, as shown and described.

DESCRIPTION

FIG. 1 shows a display screen or portion thereof with graphical user interface showing our new design; and, FIG. 2 shows a second embodiment thereof.

The peripheral dashed broken lines illustrate a display screen or portion thereof which form no part of the claimed design. The interior broken lines illustrate portions of the graphical user interface which form no part of the claimed design.

1 Claim, 2 Drawing Sheets
